1. A gas mixing apparatus comprising front and rear casings, a partition separating the two casings and having a centrally arranged opening therein connecting the two casings together at their structural portions, the front casing having a centrally arranged inlet in its front part adapted to receive a mixture of fuel vapor and air, a rotary shaft passing through the rear casing, through the opening in the partition and extending

UNITED STATES PATENT OFFICE

2,012,570

GAS MIXING APPARATUS

Charles A. Kutcher, Sheridan, Wyo.

Application June 22, 1934, Serial No. 731,967

2 Claims. (Cl. 48—188)

This invention relates to a gas mixing apparatus for internal combustion engines, the general object of the invention being to provide simple means for thoroughly mixing the fuel and air passing from a carburetor to the engine so that the efficiency of the engine will be greatly increased and the consumption of fuel reduced.

This invention also consists in certain other features of construction and in the combination and arrangement of several parts, to be herein-after fully described, illustrated in the accompanying drawings and specifically pointed out in the appended claims.

In describing the invention in detail, reference will be had to the accompanying drawings wherein like characters denote like or corresponding parts, throughout the several views, and in which:—

Figure 1 is a vertical sectional view through the mixing apparatus.

Figure 2 is a section on line 2—2 of Figure 1.

Figure 3 is a section on line 3—3 of Figure 1.

Figure 4 is a fragmentary perspective view of the vanes on their supporting rings, these parts being mounted in the furcations.

Figure 5 is a fragmentary perspective view of the corrugated lining of the second casing.

In these drawings, the letter A indicates a housing which is constructed to form a small casing 1 and a large casing 2, the two casings being in communication with each other through the centrally arranged opening 3 in the wall which separates the casings, and the front casing 1 is formed with a centrally arranged inlet opening 4 surrounded by a flange 5 which is adapted to be connected with the outlet of the carburetor (not shown). Front and rear rings 6 are arranged in the casing 1 and are concentric to the opening 4 and these rings support the vanes 7 which are spaced apart and are preferably set at angles of about 30 degrees to the radius of the fan B which the vanes surround. The blades 8 of this fan are formed of strips having their inner ends curved and fastened to a hub

9 which is connected to the shaft 10 which passes through the casing 2 and through the boss 11 carried by the casing 2. Anti-friction bearings 12 for the shaft are arranged in the boss and packing means 13 are also arranged in the boss. A fan C is arranged in the casing 2 and is similar to the fan B and each fan has a backing disk 14 in rear of the fan and to which the blades are connected. The casing 2 is of volute shape as shown in Figure 3 so that the circumferential wall of the casing gradually increases in radius

from the hub of the fan C from one side of the outlet opening 15 of the casing to the opposite side thereof and said outlet opening 15 is adapted to be connected with the manifold or other inlet part of the engine and the fan C is eccentrically arranged in the casing and a corrugated lining 16 contacts the internal wall of the casing 2 and has its ends connected to the casing as shown at 17 in Figure 3. A sleeve 18 is placed on the shaft 10 between the hubs of the fans and the inner ends of the blades of the fans are recessed as shown at 19 in Figure 1.

The shaft can be driven from any suitable part of the engine, such as the fan shaft and as it will be seen the mixture of fuel vapor and air passes from the carburetor through the opening in flange 5 and through opening 4 into the first casing where it is acted on by the blades of the fan B which forces the mixture past the vanes 7 and against the walls of the casing 1 and then the mixture flows around the backing plate 14, through the opening 3 into the second casing where it is acted on by the blades of the second fan which throw the mixture against the corrugated lining 16 and from this second casing the mixture passes to the engine, not shown. Thus the mixture is thoroughly agitated and mixed so that its combustible qualities are increased as all small particles of liquid fuel are broken up and thoroughly mixed with the air. The device will deliver the mixture under proper pressure to the engine and the mechanical agitation of the fuel will overcome to a large degree the cooling or chilling effect of the vaporization produced by the carburetor. The invention provides a greater efficiency of the motor and economy in the use of the liquid fuel.

It is thought that from the foregoing description the advantages and novel features of the invention will be readily apparent.

It is to be understood that changes may be made in the construction and in the combination and arrangement of the several parts, provided that such changes fall within the scope of the appended claims.

What is claimed is:—

1. A gas mixing apparatus comprising front and rear casings, a partition separating the two casings and having a centrally arranged opening therein connecting the two casings together at their structural portions, the front casing having a centrally arranged inlet in its front part adapted to receive a mixture of fuel vapor and air, a rotary shaft passing through the rear casing, through the opening in the partition and extend-

ing into the front casing, a pair of fans carried by the shaft and one located in the front casing and the other in the rear casing, each fan including a hub portion connected with the shaft and outwardly extending blades connected with the hub portion, an annular row of diagonally arranged vanes surrounding the fan in the front casing, a backing plate connected to the rear end of the hub of the fan in the front casing and spaced from the partition and extending beyond the outer ends of the blades of said fan, said front fan forcing the mixture of fuel vapor and air between the vanes and against the inner circumferential wall of the front casing, the mixture passing between the backing plate of the front fan and the partition and entering the rear casing through the opening in the partition, said rear casing having an outlet connected with a part of the circumferential wall and a corrugated lining in the rear casing against which the mixture entering the rear casing is thrown by the fan in the rear casing.

2. A gas mixing apparatus comprising front and rear casings, a partition separating the two casings and having a centrally arranged opening therein connecting the two casings together at their structural portions, the front casing having a centrally arranged inlet in its front part adapted to receive a mixture of fuel vapor and air, a rotary shaft passing through the rear casing,

through the opening in the partition and extending into the front casing, a pair of fans carried by the shaft and one located in the front casing and the other in the rear casing, each fan including a hub portion connected with the shaft and outwardly extending blades connected with the hub portion, an annular row of diagonally arranged vanes surrounding the fan in the front casing, a backing plate connected to the rear end of the hub of the fan in the front casing and spaced from the partition and extending beyond the outer ends of the blades of said fan, said front fan forcing the mixture between the vanes and against the inner circumferential wall of the front casing, the mixture passing between the backing plate of the front fan and the partition and entering the rear casing through the opening in the partition, said rear casing having an outlet connected with a part of the circumferential wall and a corrugated lining in the rear casing against which the mixture entering the rear casing is thrown by the fan in the rear casing, the corrugated lining in the circumferential wall of the rear casing having its radius from the shaft gradually increasing from one wall of the outlet to the opposite wall whereby the space between the fan and said lining gradually increases in width from said first wall of the outlet to said opposite wall.
